CLOSURE FOR BOTTLES AND JARS

Original Filed Nov. 18, 1931

UNITED STATES PATENT OFFICE

2,041,768

CLOSURE FOR BOTTLES AND JARS

Alfred Kohrer, Toledo, Ohio, assignor to The
Closure Service Company, Toledo, Ohio, a cor-
poration of Ohio

Application November 18, 1931, Serial No. 575,739
Renewed October 12, 1935

7 Claims. (Cl. 215—43)

The present invention relates to improvements in closures for bottles and jars and more particularly to closures formed of metal and including inner and outer caps secured together.

5 An object of the present invention is the provision of a metal closure in which both the attaching threads and a bead which provides the finished lower edge of the threaded flange are obscured from view. The construction whereby 10 such a closure may be provided, according to the present invention, consists of inner and outer caps secured together by interlocking the lower marginal portions of the flanges in a fashion to form an internal continuous bead. The attaching 15 threads or other projections having a like function, are provided on the inner cap. Such a construction results in the provision of a closure in which the outer flange is perfectly smooth and has an unbroken surface throughout.

20 Among the advantages of this construction is the provision of a closure which may be finished in any desired color without having the color scheme broken by the presence of an external bead or/and raw edge of metal.

25 Other objects will be in part apparent and in part pointed out hereinafter.

In the drawing:

Fig. 1 is a fragmentary elevational view showing my improved closure attached to a container.

20 Fig. 2 is a sectional view of the outer cap or shell prior to attachment thereof to the inner cap.

Fig. 3 is a sectional view of the inner cap prior to assembly.

35 Fig. 4 is a sectional view showing the inner and outer caps assembled.

Fig. 5 is a detail sectional view showing the manner in which the flanges of the inner and outer caps are secured together.

40 Fig. 6 is a sectional view showing in considerable detail the manner in which the cap flanges are interlocked.

Fig. 7 is a sectional view showing in detail another form of two piece closure.

45 Fig. 8 is a fragmentary sectional view of a single piece cap in which the attaching flange is formed in accordance with the present invention.

One form of my improved closure is shown in Figs. 1 to 6 inclusive. In this form the closure 50 consists of two caps telescoped one over the other and secured together in such fashion that an internal bead is formed at the lower margin of the flanges which constitute portions of the caps. The result is the provision of a perfectly smooth 55 external flange on the finished closure, a flange entirely free from any surface irregularities. The inner cap includes a circular top portion 10 and an integral depending attaching flange 11 having threads 12 formed thereon. Below the 60 threads the flange diameter is enlarged slightly

and the walls curved outwardly, downwardly, and thence inwardly a short distance providing, in effect, a continuous inwardly facing channel 13 which is substantially U-shaped in cross-section. The exposed raw edge of the flange faces 5 inwardly and is adapted for contact with a portion of the outer cap 14 or shell as will be brought out presently.

The outer cap 14 or shell comprises a circular top 15 and a depending flange 16 thereon. The 10 flange 16 on the outer cap or shell is of somewhat greater depth than the threaded flange on the inner cap. In assembling the caps, the shell 14 is placed over the inner cap. That portion of the outer flange 16 extending beyond the screw 15 threaded flange 11 is rolled inwardly over the raw edge of the screw threaded flange and then pressed into the channel 13. In this assembly 20 operation, sufficient pressure is applied in folding the lower margin of the outer flange to cause 25 the raw edge of the attaching flange to bite into the adjacent surface of said outer flange. This feature will be apparent in Fig. 6 in which it will also be noted that the channel 13 and inwardly folded portion of the outer flange in addition 25 to securing the two caps together and preventing relative movement between the inner and outer caps, provides a stiffening bead 17 lying within the annular space defined by a vertical downward extension of the outer surfaces of the 30 completed closure and a vertical downward extension of the threaded portion of the inner cap. As a result of this construction the entire outer surface of the flange of the completed closure is perfectly smooth and does not present any raw 35 metal edges. Moreover, the raw edge of the bead 17 is protected by being projected into the channel 13 directly beneath the lower part of the screw threads. Further, the bead, although 40 formed internally of the closure, does not interfere with application of the closure to a jar or other container, and, in fact, facilitates such application because of its functioning as a guide for centering the closure upon the receptacle to be sealed thereby.

45 It will be observed that the lower marginal portion of the outer cap flange which is folded around the lower margin of the inner cap and forms the bead 17, is of greater interior diameter than the greatest interior diameter of the 50 screw threaded part of the cap. The finished cap is thus provided with an entrance portion, the diameter of which is sufficiently great to prevent interference with the screw threads on the container to which the cap is applied and permits the cap to have a close fit on the threads 55 of said container.

In another form of the invention (Fig. 7) the threaded attaching flange 12^a at the lower point of termination of the threads is extended radial- 60

ly outward and thence downwardly and inwardly forming a channel 18 which is substantially V-shaped in cross-section. The outer wall 19 of this channel converges downwardly and is adapted to project into a bead 20 provided at the lower edge of the outer flange 16^a. In this form of closure the free edge portion of the outer flange forming the bead 20 is firmly pressed against the inner surface of the downwardly converging wall 19 of the channel 18, such pressure tending to expand the wall and force it into parallelism with the outer flange 16^a and thereby producing such frictional contact between the two flanges as will prevent relative rotation or other movement of the inner and outer caps.

In Fig. 8, I have shown a form of single cap in which the lower edge portion of the threaded attaching flange 21 is rolled inwardly and upwardly to provide an obscured bead, the diameter of which is greater than that of the threads. This construction greatly facilitates application of the closure to bottles or the like containers, in addition to enhancing the appearance of the closure by placing the bead and ordinarily exposed raw edge entirely out of view.

Modifications may be resorted to within the spirit and scope of the appended claims.

What I claim is:

1. A closure comprising an inner cap having a circular attaching flange provided with screw threads, said screw threads terminating at a point short of the lower margin of the flange, said flange having that portion below the threads extended outwardly, downwardly, and thence inwardly presenting an inwardly facing edge of metal and forming an inwardly facing continuous channel, and an outer cap telescoped over the inner cap and including a depending flange, said flange having its lower marginal portion folded inwardly and thence upwardly over and in contact with said edge and into the channel to thereby secure the two caps together and form an internal continuous bead.
2. A closure comprising an inner cap having a circular attaching flange provided with screw threads, said screw threads terminating at a point short of the lower margin of the flange, said flange having that portion below the threads extended outwardly, downwardly, and thence inwardly presenting an inwardly facing raw edge of metal and forming an inwardly facing continuous channel, and an outer cap telescoped over the inner cap and including a depending flange, said flange having its lower marginal portion folded inwardly and thence upwardly over and in contact with said raw edge and into the channel to thereby secure the two caps together and form an internal continuous bead, said bead in its entirety being disposed in the annular space defined by vertical downward extensions of said outer cap flange and the screw threaded portion of the attaching flange.
3. A closure comprising an inner cap having a circular attaching flange provided with screw threads, said screw threads terminating at a point short of the lower margin of the flange, said attaching flange having that portion below the threads directed outwardly and thence converging downwardly and forming a continuous channel substantially V-shaped in cross-section, and an outer cap ar-

ranged over the inner cap and including a continuous flange, said flange having its lower end folded inwardly and upwardly to provide a continuous bead into which the downwardly converging portion of the attaching flange projects, 5 said bead being compressed sufficiently to exert an expanding pressure on said downwardly converging portion of the attaching flange and thereby securing the caps against relative movement.

4. A closure comprising an inner cap having a 10 circular attaching flange provided with screw threads, said screw threads terminating at a point short of the lower margin of the flange, said attaching flange having that portion below the threads directed outwardly and thence converging downwardly and forming a continuous channel substantially V-shaped in cross-section, and an outer cap arranged over the inner cap and including a continuous flange, said flange having its lower end folded inwardly and upwardly to 15 provide a continuous bead into which the downwardly converging portion of the attaching flange projects, said bead being compressed sufficiently to exert an expanding pressure on said downwardly converging portion of the attaching flange, 20 and thereby securing the caps against relative movement, said bead and downwardly converging portion of the attaching flange being disposed in the annular space defined by vertical downward extensions of the external surface of the outer flange and the threaded portion of the attaching flange. 25

5. A closure comprising an inner cap having a circular attaching flange provided with screw 30 threads terminating at a point short of the lower margin of the flange, said flange having that portion below the threads extended outwardly and thence downwardly and inwardly to form an inwardly facing channel, and an outer cap telescoped over the inner cap and having the lower 35 marginal portion of its depending flange folded around the lower margin of the inner cap and outwardly beneath the lower part of the threads and into the channel, the amount of outward 40 extension of the lower portion of the inner cap being sufficiently great to provide the finished closure with an entrance portion of greater interior diameter than the greatest interior diameter of the screw threaded part of the cap. 45

6. A sheet metal closure comprising an inner 50 cap having a circular attaching flange provided with screw threads, said flange having its lower marginal portion directed inwardly and presenting an inwardly facing raw edge of metal, an outer cap telescoped over the inner cap and having the lower marginal portion of its depending flange folded inwardly and upwardly into firm engagement with said raw edge to thereby secure the two caps together and against relative rotation. 60

7. A closure comprising an inner screw cap having a threaded skirt with its lower circular edge inwardly curled, an outer shell having a cylindrical depending skirt fitted over said inner 65 cap, said shell skirt having a rounded bead along its lower edge rolled inwardly over the inwardly curled edge of the cap to clamp both cap and shell in a substantially cylindrical surface alignment as a closure unit. 70

ALFRED KOHRER.
